UNITED STATES PATENT OFFICE

OWEN H. SPENCER, OF INDIANAPOLIS, INDIANA

DESIGN FOR A VEHICLE BODY

Application filed September 20, 1929. Serial No. 32,806. Term of patent 14 years.

To all whom it may concern:

Be it known that I, OWEN H. SPENCER, a citizen of the United States, residing at Indianapolis, in the county of Marion and State of Indiana, have invented a new, original, and ornamental Design for Vehicle Bodies, of which the following is a specification, reference being had to the accompanying drawing, forming a part thereof.

I claim:

An ornamental design for a vehicle body, as shown and described.

OWEN H. SPENCER.
